UNITED STATES PATENT OFFICE

126,611

DESIGN FOR A CLOCK OR SIMILAR ARTICLE

Kate Lerman, Chicago, Ill.

Application February 12, 1941, Serial No. 98,954

Term of patent 7 years

To all whom it may concern:

Be it known that I, Kate Lerman, a citizen of the United States, residing at Chicago, in the county of Cook and State of Illinois, have invented a new, original, and ornamental Design for a Clock or Similar Article, of which the following is a specification, reference being made to the accompanying drawing, forming a part thereof in which

Fig. 1 is a front elevational view of a clock embodying my new design;

Fig 2 is a top plan view of the same; and

Fig. 3 is an end elevational view thereof.

I claim:

The ornamental design for a clock or similar article, substantially as shown.

KATE LERMAN.
